MOUNTING MEANS FOR IGNITION SWITCH
LOCKS

Edward N. Jacobi, Milwaukee, Wis., assignor to
Briggs & Stratton Corporation, Milwaukee,
Wis., a corporation of Delaware

Application March 17, 1947, Serial No. 735,276

9 Claims. (Cl. 248—27)

1

This invention relates to ignition switches for automobiles and refers particularly to the mounting of such switches upon the instrument panel. Hence, this invention is a continuation in part of the applicant's pending application, Serial No. 665,879, filed April 29, 1946, now Patent No. 2,506,642, issued May 9, 1950.

The instrument panels of automobiles are now generally all provided with rearwardly directed flanges along their lower edges. Inasmuch as these flanges are hidden from view, the securement thereto of the switch retaining means enables mounting the switch on the panel without need for fastening any part of the switch or its retaining means to the upright or face portion of the panel.

It is, therefore, an object of this invention to provide an improved manner of utilizing the rearwardly directed flange along the bottom of the panel for anchoring a retaining device by which the ignition switch may be quickly and easily mounted in position.

Another object of this invention is to provide an ignition switch retaining device which incorporates a spring element serving the dual function of holding the retaining device attached to the flange at the lower edge of the panel and holding the switch firmly against the back of the panel with a force sufficient to prevent rattling and adequate to resist normal inward pressure applied to the front of the switch or its key during use.

Another object of this invention is to provide means for mounting an ignition switch or other instrument in back of a panel, wherein the need for rivets, spot welding or other fastening expedients is obviated by a novel snap spring fastening means securing the retaining device to the rearwardly extended flange along the bottom edge of the panel.

In key controlled ignition switches the lock cylinder is insertable into its casing through an open front end, and some means must be provided for holding the cylinder in place in the casing. The present invention has as another of its objects, to provide means for performing this function as an incident to the securement of the ignition switch to the back of the panel.

Still another object of this invention is to provide means for illuminating the keyhole or front of the ignition switch, incorporated as part of the means for mounting the switch in back of the panel.

With the above and other objects in view, which will appear as the description proceeds, this in-

2

vention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate several complete examples of the physical embodiment of the invention constructed according to the best modes so far devised for the practical application of the principles thereof, and in which:

Figure 1 is a cross-sectional view through an instrument panel of an automobile showing one adaptation of this invention;

Figure 2 is a front view of part of the structure shown in Figure 1;

Figure 3 is a cross-sectional view taken through Figure 1 on the plane of line 3—3;

Figure 4 is a view similar to Figure 1, but on a somewhat larger scale, illustrating the way in which part of the switch mounting means may be used to enable illumination of the keyhole or front of the ignition switch;

Figure 5 is a view similar to Figure 1 but showing another adaptation of this invention;

Figure 6 is a rear view of the structure shown in Figure 5;

Figure 7 is a cross-sectional view through an instrument panel, as in Figure 1, but illustrating another form of the invention;

Figure 8 is a cross-section view taken on the plane of line 8—8 in Figure 7; and

Figure 9 is a perspective view of the front end of the switch device shown in Figure 7 and the bezel structure for securing the lock cylinder in position, said parts being shown separated.

Referring now more particularly to the accompanying drawings in which like numerals indicate like parts, the numeral 5 designates the face or upright portion of an instrument panel of the type generally found in automobiles. The panel has the customary rearwardly directed horizontal flange 6 along the lower edge thereof. A round hole 7 is provided in the upright portion of the panel to receive the front end of an ignition switch device 8.

The ignition switch device 8 may be of any conventional design as it forms no part of this invention. It is sufficient to note that the switch device includes a casing 9 and a rotatable lock cylinder 10 inserted into the casing through the open front end thereof. Being thus assembled with the casing some means must be provided to hold the cylinder in place. This function is

performed as an incident to the securement of the switch device to the back of the panel, as will be more fully described hereinafter.

The lock cylinder 10 is adapted to receive a key 11 which thus provides the handle for turning the cylinder and actuating the contactor of the switch (not shown) by which opening and closing of the switch is effected. As will be readily appreciated, the switch is connected in the circuit it controls by conductors (not shown) attached to terminals 12.

In all forms of the invention illustrated, the front of the lock cylinder 10 is covered by a cap 13 stamped from sheet metal and polished to present a neat appearance. This cap has an outwardly directed annular flange 14 which underlies the inner peripheral portion of a bezel ring 15. The bezel ring is of a size to fit the round hole 7 in the instrument panel and is shouldered and flanged as at 16 to fit the front end of the casing 9 and engage the back face of the panel. Thus by pressing the casing 9 toward the panel the bezel ring 15 is held in place and this in turn secures the lock cylinder 10 against removal from the casing.

In that form of the invention shown in Figure 4, the bezel ring incorporates means for illuminating the front of the keyhole in the panel. To this end the bezel ring 15 has a collar 17 of translucent material, for instance "Lucite," mounted thereon. An auxiliary bezel ring 18 shrouding the "Lucite" collar fits the hole in the panel 5, and provides the shoulder to bear against the back of the panel.

The bezel construction employed in that form of the invention shown in Figures 7, 8 and 9 is modified from that shown in Figure 1 to the extent that the bezel ring 15 has two diametrically opposite pairs of hooks 19 to engage over lugs 20 and 21 projecting radially from the casing. Also, in this case the bezel ring fits the full diameter of the casing whereas in Figure 1 it is mounted on a reduced front end portion of the casing. Thus in the modified embodiment shown in Figures 7, 8 and 9, the bezel ring has a flange 22 which provides the means for engaging the back of the panel to hold the switch device against forward displacement.

In all forms of the invention shown, a lug 23 struck from the bezel ring engages in a notch 24 in the edge of the hole 7 to hold the switch device against turning.

In the form of the invention shown in Figures 1 to 6 inclusive, the casing 9 has diametrically opposite abutments or lugs 25 projecting from opposite sides and a spring retaining device indicated generally by numeral 26, engages against these lugs to urge the ignition switch against the back of the panel.

The retaining device 26 shown in Figures 1 to 3 inclusive is formed from a length of spring wire initially bent to substantially hairpin shape. Its closed end is formed into a hook 27 engageable over the upturned marginal edge portion 28 of the rearwardly directed flange 6; and at a medial point both legs of the hairpin are coiled into torsion springs 29. The free end portions 30 of the legs of the hairpin project from the torsion springs substantially at right angles to its closed end portion 31. These free end portions 30 extend through holes 32 in the flange 6 when the retaining device is snapped onto the flange and the extremities thereof bear against the lugs 25.

Thus when the retaining device is in position, the torsion springs 29 bear against the underside

of the flange 6 and the free end portions 30 provide resilient arms embracing the casing of the switch device and acting against the lugs 25 to press the casing firmly against the back of the panel. In applying the retaining device the free end portion 30 are first inserted into the holes 32 and positioned against the lugs 25 while the switch device is manually held in position. The hook 27 is then snapped over the edge 28 of the flange.

The portion of the retaining device from the torsion springs 29 back to the hook 27 thus constitutes an anchoring part while the arms 30 provide spring means for pressing the switch device against the back of the panel.

In the construction shown in Figures 5 and 6, the spring retaining device 26 is stamped from flat spring stock and has a substantially U-shaped or bifurcated plate portion 33 to embrace the switch 20 casing and engage the lugs 25. At the closed end 30 of this bifurcated U-shaped portion, the stamping is bent into an S-shaped configuration having two loops 34 and 35. A tang 36 is struck outwardly from the loop 34 to project through a hole 37 in the flange 6 and engage over the rear edge thereof. The loop 35 has an extended straight extremity 38 from which a tang 39 is struck inwardly. This tang 39 is so positioned that when the loop 34 rests upon the upper face of the flange 6 and its tang 36 projects into the hole 37, upward flexure of the straight extremity 38 from its position shown in dotted lines in Figure 5 brings the tang 39 in position to be hooked over the upturned marginal edge 28. So engaged, the spring retaining device is anchored to the flange 6 in a manner permitting its bifurcated U-shaped portion 33 to flex toward and from the panel and thus perform its function of holding the switch casing against the back of the panel.

The retaining means employed in Figure 4 may be identical to that shown in Figure 1, but in this case a suitable light source 40 is mounted on the switch casing to shine through and illuminate the translucent bezel portion 17.

In Figures 7, 8 and 9, the spring tension for pressing the switch casing against the back of the panel is provided by a coil spring 41 encircling the casing and reacting between an anchor or supporting structure 42 and a ring 43 bearing against the lugs 20 and 21. The ring 43 has an open gate 44 and a notch 45 to accommodate the lugs 20 or 21. By having one of the lugs longer than the other, the assembly and disassembly of the ring with the casing can be effected in only one position of relative rotation.

The supporting or anchoring device 42 is a stamping of spring metal and has a flat wall 46 apertured to receive the casing 9. The side edges of this flat wall are stiffened by flanges 47, one of which has a rearwardly and downwardly directed extension 48 with a notch 49 in the outer extremity thereof for engagement over the upturned marginal edge 28 of the flange 6. The extremity of this arm 48 also has a laterally directed tongue or handle portion 50 which may be grasped by a pair of pliers to facilitate the application of the device.

At the bottom of the flat wall 46 are two downwardly projecting legs 51 reinforced by beads 52 and provided with hooks 53 to engage over edges of holes 54 in the flange 6.

In mounting the ignition switch with the retaining device as shown in Figures 7 to 9 inclusive, the supporting or anchoring member as well

as the spring 41 are first assembled with the switch, and then the front end of the switch device is inserted into the hole 7 in the panel. This done, the legs 51 are inserted into the holes 54, and thereafter the arm 48 is sprung to snap the marginal flange 28 into the notch 49.

From the foregoing description taken in connection with the accompanying drawings, it will be readily apparent that this invention provides a simple inexpensive manner of quickly mounting an ignition switch on the instrument panel of an automobile.

What I claim as my invention is:

1. Means for mounting an instrument in position on the back of an instrument panel of the type provided with a rearwardly directed flange along its lower edge and having an aperture in an upright portion of the panel to receive a reduced end portion at the forward extremity of the instrument to locate the same and to expose the reduced extremity of the instrument to view at the front of the panel, comprising: a spring member having an anchoring portion removably hooked onto said rearwardly directed flange, and having spaced arms extending upwardly from the flange to embrace the sides of the instrument and engage abutments thereon, attachment of the retaining device to the rearwardly directed flange tensioning the spring arms in the direction to press the instrument against the back of the panel.

2. Means for mounting an instrument in position on the back of an instrument panel of the type provided with a rearwardly directed flange along its lower edge and having an aperture in an upright portion of the panel to receive a reduced end portion at the forward extremity of the instrument to locate the same and to expose the reduced extremity of the instrument to view at the front of the panel, comprising: a spring member having a part readily removably hooked onto the edge of said rearwardly directed flange and having a spring arm extending upwardly from the flange alongside the instrument, the attachment of said spring member to the flange tensioning the spring arm so that said spring arm is biased toward the back of the panel; and an abutment on the instrument engaged by the spring arm whereby said biasing force of the spring arm holds the instrument firmly against the back of the panel.

3. A spring retaining device for holding an ignition switch in position in back of the instrument panel of an automobile, comprising: a length of spring wire bent substantially into a hairpin shape with its closed end formed into a hook for engagement over the edge of a flange on the panel and with the legs of the hairpin coiled into torsion springs at a point medially of the legs, so that upon attachment of the hooked closed end of said spring device over the edge of a rearwardly extending flange along the bottom of the instrument panel, the free end portions of the legs of the device may protrude upwardly through holes in the flange to provide means for pressing the switch against the back of the panel.

4. A spring retainer for holding an ignition switch against the back of an instrument panel equipped with a rearwardly directed flange along the lower edge thereof, comprising: a substantially U-shaped spring clip, the arms of which are adapted to embrace the body of the ignition switch with the extremities thereof pressing against abutments thereon, the closed end of the

U-shaped spring clip having a substantially S-shaped curvature; a tang projecting outwardly from the curve of the S nearest the outer arms of said clip, said tang being adapted to engage in a hole in the rearwardly directed flange when said clip rests on the top of said flange; and a tang struck inwardly from the outer end portion of the other curve of the S and positioned to hook over the marginal edge of the rearwardly directed flange to thus anchor the spring clip to the flange.

5. Means for mounting an instrument on the back of an instrument panel of the type provided with a rearwardly directed flange along its lower edge and having an aperture in the upright portion of the panel to receive the front end portion of the instrument to locate the same and expose the front end of the instrument to view at the front of the panel, comprising: a shoulder on the front end portion of the instrument engaging the back of the instrument panel and preventing forward displacement of the instrument with respect to the panel; a spring support detachably secured to the rearwardly directed flange and extending upwardly therefrom with a portion thereof embracing the medial part of the instrument; an abutment on the forward portion of the instrument; and a coil spring encircling the instrument and reacting between said abutment and the spring support.

6. Means for holding an ignition switch of the type having a lock cylinder inserted into the body of the switch through the front end thereof, to the back of an instrument panel, comprising: a bezel ring on the front end of the switch casing engaging over a part of the lock cylinder; abutments projecting from the side of the casing; means on the bezel ring engaging over said abutments to hold the bezel ring in position on the front end of the casing; a flange on the bezel ring engaging the back of the instrument panel with a portion of the bezel ring protruding through a hole in the instrument panel; an anchor part secured behind the instrument panel; and spring means reacting between said abutments and said anchor part to firmly hold the switch device against the back of the panel.

7. In combination with a key controlled ignition switch having a bored casing and a lock cylinder mounted therein: means for mounting the ignition switch in back of an instrument panel with the front of the lock cylinder exposed to view at the front of the panel through a hole therein, said means including a bezel ring encircling the front end of the casing and received in the hole in the panel, part of said bezel ring being translucent; and a light mounted behind the panel and adjacent to the switch device to illuminate said translucent part of the bezel ring and thus facilitate location of the keyhole at night.

8. A support for an instrument of the type having a reduced portion at its forward extremity and a forwardly facing shoulder immediately behind said reduced portion, said support being adapted to mount said instrument on a panel of the type having an aperture in an upright portion thereof adapted to receive said reduced portion of the instrument to locate the same and to expose it to view at the front of the panel and having a rearwardly directed flange along its lower edge, said support comprising: a rear part having a forwardly extending portion providing a hook having a downwardly facing abutment adapted to engage over and bear downwardly upon the rear edge of said flange; a forward part

connected with said rear part and having means thereon providing an upwardly facing abutment spaced forwardly of said hook on the rear part and adapted to engage the underside of said flange intermediate the rear edge thereof and the upright panel; a rearwardly facing abutment on the support adapted to engage a forwardly facing abutment on said flange; and means for applying a yielding force to said instrument to urge the shoulder thereon into firm engagement with the back of the panel, said means including an upright part on said support having spaced members extending upwardly from said forward part and adapted to embrace a portion of the instrument and to directly receive the reaction of said forward force and to translate said reaction into a rearward reaction on said rearwardly facing abutment, a downward reaction on said abutment on the hook on said rear part and an upward reaction on said abutment on the forward part to urge them into engagement with said flange.

9. In an installation of the type in which an instrument having a reduced portion at its forward extremity and a forwardly facing shoulder immediately behind said reduced portion is mounted on an instrument panel having an aperture in an upright portion thereof and in which said reduced portion is received to locate the instrument and to expose it to view at the front of the panel, said panel also having a rearwardly extending flange beneath said aperture therein: means for applying a yielding forward force to the instrument to hold the shoulder thereon against the back of the panel, said means including a forwardly disposed part including

spaced upright members adapted to embrace the instrument; a member connected with said upright member and extending rearwardly therefrom to lie at one side of the flange and long enough to project to the rear edge of the flange; a downwardly facing abutment on the rear extremity of said rearwardly extending member adapted to engage the flange and to thereby transmit part of the reaction force on said upright part through the rearwardly extending part downwardly into the flange; and means on the lower portion of the upright member adapted to pass through an opening in the flange to the underside thereof, said means including an upwardly facing abutment spaced forwardly of said downwardly facing abutment and adapted to engage the underside of the flange and a rearwardly facing abutment adapted to engage the flange at the front edge of the hole therein to transfer the remainder of the reaction force on the upright member to the flange.

EDWARD N. JACOBI.
